TURRET HEAD WRENCH

Thomas J. Dossie, New York, N.Y.

Application October 3, 1952, Serial No. 312,896

6 Claims. (Cl. 81—57.5)

1

This invention relates to wrench devices and, particularly what I term a turret head wrench, wherein a plurality of wrench elements of different diameters are supported in a head and means is provided for moving the wrenches into extended operative position and, wherein, the head includes a handle portion which, in itself, can be utilized as a wrench. Still more particularly, the invention deals with a wrench device of the character described, wherein tensional means is employed to normally support the tools in inoperative position within the environment of the head of the tool.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a side and sectional view of one form of tool which I employ, illustrating the handle member in full and dotted lines in two different positions, with parts of the construction broken away.

Fig. 2 is a section on the line 2—2 of Fig. 1.

Fig. 3 is a sectional view through a modified form of tool with the handle member broken away and also indicating the parts in a different position in dotted lines; and

Fig. 4 is a section on the line 4—4 of Fig. 3.

In Figs. 1 and 2 of the drawing, I have shown at 10 a tool body or head having a hexagon bore 11 extending therethrough and eccentrically disposed with respect to the head, the body having a plurality of hexagon bores 12 arranged in close proximity to the peripheral edge of the body, as clearly seen in Fig. 2. The bores 12 are of different diameters to receive tool or wrench elements 13 of different diameters fitting snugly in the apertures 12. The body 10 has an annular groove 14 which opens into all of the bores 12 and in the groove 14 is disposed a coil spring 15, sufficiently tensioned to establish a frictional engagement with all of the tools 13 to normally support the same within the environment of the body or head 10, including an upwardly extending sleeve portion 16 thereof. In normal position of the tools or wrenches 13, they are contained within upper and lower surfaces of the head 10 and, when it is desired to use one of the tools, a handle member 17 is inserted in the bore 11 and, in this operation, a radially offset lug portion or dog 18, for example, on the long end 17' of the handle member, en-

gages a selected tool 13 and advances this tool into the extended position, as shown at 13' in Fig. 1 of the drawing. The end 17' includes a tensioned ball 19 to establish frictional engagement of the handle member in the bore 11. The other short end 17'' of the handle member also has a projection or dog 18' and a ball 19' facilitating coupling of the short end with the head when it is desired to extend the long end 17' of the handle member in the horizontal direction or what might be said to be radially with respect to the head 10.

Either one of the spring actuated balls 19, 19' will establish sufficient frictional engagement to support the head on the handle member in either use of the tool.

Considering Fig. 2 of the drawing, it will appear that the six sides of the bore 11 face each of the bores 12 so that the lug or dog 18, 18' which is on one of the flat surfaces of the hexagon handle member will be in alignment with one of the tools 13 so that, in moving the handle member into the bore 11 and axially of the head, the dog 18, 18' will engage and project the tool 13 registering with said dog. When the handle member is detached, the previously projected tool 13 can be returned to collapsed position by pressing inwardly by hand.

In Figs. 3 and 4 of the drawing, I have shown another form of construction, wherein 20 represents a head, generally similar to the head 10, with the exception that the sleeve 16 is dispensed with as is also the groove 14 and spring 15. Further, in Figs. 3 and 4, a short hexagon bore 21 is provided and this bore is arranged concentrically with respect to the body 20. Eccentrically arranged with respect to the bore 21 are a plurality of hexagon bores 22 of different diameters in which are arranged hexagon tools or wrenches 23. Inner ends of the wrenches 23 have extended collars or flanges 24 which form seats for springs 25, which normally support the wrenches in raised retracted position, as seen at the right of Fig. 3.

The bore 21 opens into a large diameter bore 26 in which is fixed, by a set screw 27, a sleeve 28 which forms a bearing support for a key pin 29. The pin 29 has a collar 30 fixed thereto adjacent the hexagon end 31 of the pin. This collar forms a seat for a spring 32 arranged in the sleeve 28 and normally serving to support the pin 29 in operative position in the hexagon socket or bore 21.

Keyed to the pin 29 is a disc 33, to which is fixed a radially extending hexagon handle mem-

ber 34. The disc 33 has a depending sleeve 35, substantially of the same diameter as the body 20 and serves to house the upper end portion 32 of the tools, as will clearly appear from a consideration of Fig. 3 of the drawing.

Also fixed to the disc 33 and arranged within the sleeve 35 is a tool operating pin 36 having a rounded lower end 37. This pin is adapted to engage any one of the six tools or wrenches 23 and is so positioned on the disc 33 as to engage all of the wrenches, regardless of the size thereof. Whenever desired, the handle member 34, including the disc 33, can be raised against the action of the spring 32 into the dotted line position shown in Fig. 3 and, in the raised position, can be rotated with respect to the body 20 to bring the operating pin 36 in registering position with any one of the six tools or wrenches supported in the head 20, after which, the disc 33 can be released and the spring 32 will operate to extend the selected tool or wrench in the manner illustrated at the left of Fig. 3 of the drawing. The body 20 and disc 33 are preferably knurled to facilitate relative rotary movement one with respect to the other.

When the handle member is in the operative position shown in full lines in Fig. 3, the handle member is definitely keyed to the body by engagement of the hexagon end 31 with the hexagon bore 21. However, in the raised position of the handle member, 31 clears 21.

It will be apparent that the handle member 17 forms a seventh wrench which can be utilized in either position and inserted into the body 16 through either end thereof.

The end 17'-17" of the handle member and the end 31 of pin 29 may be said to form stems operating in the hexagon bores 11 and 21, respectively in rotation of the tools.

Having fully described my invention, what I claim as new and desire to secure by Letters Patent is:

1. A tool of the character described, comprising a body having a plurality of circumferentially spaced bores of hexagonal cross-sectional form, each of said bores being of different dimensions, tools fitting snugly, but freely, in said bores, resilient means normally supporting the tools in retracted position within said body, a handle member including a stem adjustably supported in said body, the handle member including a part arranged radially with respect to said stem, and said part including a portion spaced from said stem a distance sufficient to selectively engage each of the tools supported in said body to individually move said tools into extended position with respect to the body against the action of said resilient means.

2. A tool of the character described, comprising a body having a plurality of circumferentially spaced bores of hexagonal cross-sectional form, each of said bores being of different dimensions, tools fitting snugly, but freely, in said bores, resilient means normally supporting the tools in retracted position within said body, a handle member including a stem adjustably supported in said body, the handle member including a part arranged radially with respect to said stem, said part including a portion spaced from said stem a distance sufficient to selectively engage each of the tools supported in said body to individually move said tools into extended position with respect to the body against the action of said resilient means, the body having a bore in which the stem of the handle member is arranged, and

said handle member including an end portion extending radially with respect to said body.

3. A tool of the character described, comprising a body having a plurality of circumferentially spaced bores of hexagonal cross-sectional form, each of said bores being of different dimensions, tools fitting snugly, but freely, in said bores, resilient means normally supporting the tools in retracted position within said body, a handle member including a stem adjustably supported in said body, the handle member including a disc portion arranged radially with respect to said stem, said disc portion including a pin spaced from the stem a distance sufficient to selectively engage each of the tools supported in said body to individually move said tools into extended position with respect to the body against the action of said resilient means, and said handle member including an end portion extending radially with respect to said body and stem.

4. A tool of the character described, comprising a body having a plurality of circumferentially spaced bores of hexagonal cross-sectional form, each of said bores being of different dimensions, tools fitting snugly, but freely, in said bores, resilient means normally supporting the tools in retracted position within said body, a handle member adjustably supported in said body and including stem ends, each having a part arranged radially with respect to the stem ends, said parts including portions spaced from the stem ends a distance sufficient to selectively engage the tools supported in said body to individually move said tools into extended position with respect to the body against the action of said resilient means, the stem ends of the handle member being hexagonal in cross-sectional form, said body having a hexagonal bore opening through both ends thereof for reception of either of said stem ends, and said last named bore being disposed eccentrically with respect to the tool bores.

5. A tool of the character described, comprising a body having a plurality of circumferentially spaced bores of hexagonal cross-sectional form, each of said bores being of different dimensions, tools fitting snugly, but freely, in said bores, resilient means normally supporting the tools in retracted position within said body, a handle member adjustably supported in said body and including stem ends, each having a part arranged radially with respect to the stem ends, said parts including portions spaced from the stem ends a distance sufficient to selectively engage the tools supported in said body to individually move said tools into extended position with respect to the body against the action of said resilient means, the stem ends of the handle member being hexagonal in cross-sectional form, said body having a hexagonal bore opening through both ends thereof for reception of either of said stem ends, said last named bore being disposed eccentrically with respect to the tool bores, said tool bores being disposed adjacent the periphery of said body, the body having a circumferential groove opening into all of said tool bores, and said resilient means comprising a coil spring fitting in said groove and engaging the tools supported in said bores.

6. A tool of the character described, comprising a body having six circumferentially spaced tool bores of hexagonal cross-sectional form, each of said bores being of different dimensions, the body, inwardly of said tool bores, having a hexagonal bore opening through both ends thereof, six tools fitting snugly, but freely, in said tool

bores, resilient means normally supporting the tools in inoperative position in said body, another handle member tool having angularly disposed stem ends of hexagonal cross-sectional form, said stem ends each including a lug arranged radially with respect thereto, and each of said lugs including a portion spaced from the stem ends a distance sufficient to selectively engage each of the six tools supported in said body to individually move said tools into extended position with respect to the body against the action of said resilient means.
